GAS BURNER

Harold D. Schrader, Great Falls, Mont., assignor
to Sullivan Valve and Engineering Company,
Butte, Mont., a corporation of Montana

Application May 3, 1941, Serial No. 391,783

5 Claims. (Cl. 158—99)

This invention relates to gas burners and particularly to up-shot radiant gas burners for use under boilers, furnaces and the like.

Objects of the invention are to provide gas burners of novel design in which the radiant surface extends over a larger part of the burner assembly than has been possible heretofore, and in which the jets of flame span the secondary air space and sweep along the surfaces of the radiants. An object is to provide a radiant gas burner in which the radiants extend over the burner outlets and are so shaped as to deflect any falling debris from the radiant surfaces and the burner openings. A further object is to provide a gas burner of the radiant type in which the burner heads are formed as units that may be assembled in various relations to meet different space requirements. Another object is to provide radiant gas burner heads of novel design that prevent a flash-back into the primary mixing chamber, that permit discharge of the air-gas streams at a desired angle to the horizontal plane of the burner casting, and that furnish a low pressure or trickle flame that may be used alone or as a stabilizer for a larger volume, high pressure gas flame.

These and other objects and advantages of the invention will be apparent from the following specification when taken with the accompanying drawings in which:

Fig. 1 is a fragmentary vertical section through a boiler combustion chamber in which a gas burner embodying the invention is installed;

Fig. 2 is a schematic horizontal section taken on the plane of line 2—2 of Fig. 1, the burner being shown in elevation;

Fig. 3 is a fragmentary elevation, on an enlarged scale and partly in vertical section, of two burner units;

Fig. 4 is a plan view, partly in section and on the same enlarged scale, of the burner units of Fig. 3;

Fig. 5 is a side elevation, with parts in section, of two double burner units arranged at right angles to each other, the section at the right side of the view being taken along a plane passing vertically through the longer axis of the radiant in the relative position indicated by plane A—A through the axis of a radiant at the left of the view;

Fig. 6 is a plan view of the radiant elements of the burner units of Fig. 5;

Figs. 7 and 8 are side elevations, partly in section, of other burner head constructions;

Fig. 9 is a fragmentary vertical section through

a combustion chamber and another multiple head burner construction embodying the invention; and

Fig. 10 is a plan view of a burner assembly comprising arcuate burner heads of different size.

The furnace structure illustrated in Figs. 1 and 2 is typical of the combustion chambers in which the new gas burner may be installed, but the furnace structure forms no part of the present invention.

In Fig. 1, the reference numeral 1 identifies one of the gas supply pipes or manifolds that are provided with gas orifices 2 upon which the primary mixing chambers or Venturi tubes 3 are mounted. The upper ends of the Venturi tubes are of rectangular shape, as shown in Fig. 2, and have integral lugs 4 that space the tubes from each other to provide passages for secondary combustion air. Prismatic bodies 5 of insulating refractory material are supported on each Venturi tube and, as will be explained later, jets of flame are projected upwardly from the top of each Venturi tube 3, along paths indicated by the broken lines a, to span the secondary air passages and to sweep along the surface of the radiant 5 of an adjacent tube.

The complete burner assembly of Figs. 1 and 2 is of rectangular form to fit within a combustion chamber of that shape, and comprises two sets of four burner heads operating from two gas pipes 1. These pipes are connected to the main gas supply line 6 through a diaphragm operated valve 7 that is controlled by a thermostatic regulating apparatus 8 in any desired manner. A small pipe 9 is connected to the supply line 6 above the diaphragm valve to furnish gas to pilot flame chambers 10 that are located at corners of certain of the Venturi tubes 3, see Fig. 2.

A large volume of gas flows through the gas pipes 1 and enters the mixing chambers 3 at high pressure when the valve 7 is fully open; and a small volume, low pressure supply of gas is delivered to the burner heads through the pipe 11 that extends from the supply pipe 6 to the small air-gas mixing chamber 12 at the inlet end of the low pressure air-gas pipe 13. The outlets for the high pressure and the low pressure air-gas mixtures will be described later.

Combustion air enters the furnace chamber through inlet passages 14 and 15 that have dampers 16 and 17, respectively, controlled by the regulating device 8. The air streams from the passages 14 and 15 are separated at the fore part of the combustion chamber by an upwardly inclined baffle plate 18, and the air stream

of passage 15 thereby supplies secondary air to the burner heads at the front of the furnace chamber while the air stream of passage 14 supplies primary air to all of the mixing chambers 3 and secondary air for the burner heads at the rear of the furnace chamber.

Each burner head includes a sleeve or distribution member 19 that is fitted within the upper end of the Venturi tube 3, see Figs. 3 and 4. The upper part of the member 19 flares outwardly and the inner surfaces of the flaring walls are notched or corrugated, by the integral ribs 20, to form a series of upwardly inclined flame jet outlets when the cap member 21 is seated within the member 19. A prismatic radiant 5a is mounted on the cap member 21, and the sloping surfaces of the radiants lie substantially in the inclined plane of the flame jets of adjacent burner heads. The ribs 20 of adjacent distribution members are staggered and the resulting series of non-intersecting flame jets follow the paths indicated by the broken lines *a* of Figs. 3 and 4, i. e. the flame jets cross the path of the secondary air and then sweep along the surfaces of the radiants.

The upper end of the Venturi tube 3 is set back from the outer flaring surface of the distribution element 19 to provide a low pressure chamber 22 that extends around the top portion of the tube 3, except at the previously described pilot flame chambers 10, and receives a low pressure air-gas mixture from the pipe 13. Notches 23 in the lower outer edge of the member 19 provide outlet openings, just below the level of the high pressure openings, for the low pressure chamber 22 and for the pilot flame chamber 10. Small ports 24 may extend through the member 19 to by-pass a limited quantity of the main air-gas mixture to the low pressure chamber 22 to supplement, or to replace, the supply through the inlet pipe 13.

The configuration of the prismatic radiant bodies 5a of Figs. 3 and 4 differs somewhat from the radiants 5 of Figs. 1 and 2, but the burner heads of Figs. 1 to 4 have the same general operating characteristics. A maximum heat demand results in a full opening of the diaphragm valve 7 and a supply of high pressure gas to the pipes 1. Any tendency towards a blow-out of the high velocity flames from the interspaces between ribs 20 of the member 19 is offset by the stabilizing action of the low pressure flames projected from the chamber 22 through the notches 23. A low heat demand that results in a closing of the diaphragm valve 7 does not interrupt the supply of gas to the low pressure chamber 22 through the pipe 11.

As illustrated in Fig. 5, each Venturi tube 3a may be bifurcated at its upper end to terminate in sections 3b of rectangular form and with notched upper edges upon which prismatic radiants 5b are retained by embedded wires 28 and springs 27 that extend between the lower ends of the wires 28 of adjacent radiants 5b. Baffles or screens 29 are retained within the branches of the Venturi tube by the radiants 5b, and serve to equalize the flow of the air-gas mixture around the periphery of the burner head and to preclude a flash-back into the primary mixing chamber. A conventional pilot burner 28 may be positioned adjacent the burner heads to replace the internal pilot flame chambers of the previously described embodiments of the invention. When the outline of each double burner head is square, as viewed in plan, all radiants

5b may be parallel to each other or, as illustrated, adjacent burner units may be displaced angularly by 90°.

As shown in Fig. 7, the Venturi tubes 3c may have cross ribs 3' to which trough-shaped members 19c are secured by screws 19', the members 19c having lower ribs 20c that space the members 19c from the tubes 3c to provide the outlet openings for the combustion gas jets. Radiants 5c are seated in the trough-shaped members 19c, and diffusion screens or baffles 28c are clamped to the ribs 3' by the members 19c.

The embodiment of the invention that is shown in Fig. 8 comprises a Venturi tube 3d that terminates at its upper edge in ribs 31 that support the distribution member 19d upon which the radiant 5d is seated. The lower sleeve of member 19d has a plurality of small openings 32 that connect the mixing chamber of the tube 3d with the air-gas chamber 33 that is formed between the member 19d and the inner wall of the Venturi tube 3d. The small openings 32 equalize the flow of the air-gas mixture into the different parts of the chamber 33, and also prevent a flash-back of the flame into the main mixing chamber in the event of a fluctuating gas pressure or other disturbing condition.

In the embodiment shown in Fig. 9, the gas supply pipe 1' extends into the Venturi inlet 39 of an air-gas manifold 34 upon which the burner head castings 35 are mounted by tapering joints. The burner heads may be of any of the described types and, as illustrated, include distribution members 19e similar to those shown in Fig. 8. The ports 32' are inclined, however, to increase the protection against a flash-back. The radiants may be of the previously described geometry or, as illustrated, may be flat topped members 5e of either circular or rectangular cross-section. The radiants have beveled edges to obtain the "scrubbing" action of the flame jets along the surfaces of the radiants. The Venturi inlet 39 is located within a metal box 36 to which the supply of primary combustion air is controlled by a damper 37. The air inlet box has another opening for admitting secondary air to the furnace chamber under control of the damper 38. Both dampers are adjusted automatically by a modulating regulating device, not shown, of any desired or known design. This independent control of the primary and the secondary air increases the efficiency of operation and prevents a flash-back into the primary mixing chambers when the main gas valve to the burner assembly is opened. A separate pilot flame unit may be provided or, as shown, a supply line 9 may lead to the pilot flame chamber 10 in one unit of the burner assembly.

The previously described embodiments of the invention include burner head units of rectangular form but, as shown in Fig. 10, arcuate burner heads with radiants 5f, 5g of different diameters may be employed to form a concentric arrangement of coaxial burner head units.

It is to be understood that the described embodiments of the invention are typical of appropriate constructions, and that other variations in the design and relative arrangement of the units fall within the spirit of my invention as set forth in the following claims.

I claim:

1. In a gas burner comprising a vertically disposed Venturi tube member having gas and air inlets at its lower end, a distribution member seated in the upper end of said Venturi tube

member and an insulating refractory radiant member seated on said distribution member, one of said distribution and refractory radiant members having spaced ribs to provide flame jet outlets for the air-gas mixture from said Venturi tube member and said radiant member extending laterally at least as far as said distribution member, the improvement consisting in that said radiant member has an upper surface which slopes outwardly and downwardly at an angle of about 45° to the horizontal to the lateral boundary thereof, the intersection of said surface with a vertical plane in the direction of the maximum slope thereof being a straight line, and that said flame jet outlets are directed outwardly and upwardly at substantially right angles to said surface.

2. A gas burner as defined in claim 1 comprising a plurality of individual burner units so positioned and spaced from each other that flame jets of each burner unit are directed parallel and adjacent to a sloping surface of the radiant member of an adjacent burner unit.

3. In an up-shot gas burner, a Venturi tube enclosing a high pressure gas chamber, an air inlet and a gas inlet at the lower end of the Venturi tube for supplying high pressure gas mix-

ture to said high pressure gas chamber, wall means within said Venturi tube and cooperating therewith to form a low pressure gas chamber surrounding said high pressure gas chamber, low pressure flame jet openings extending from said low pressure chamber between said wall means and said Venturi tube, an insulating refractory radiant closing the upper end of said high pressure chamber and cooperating with said wall means to define high pressure flame jet openings, and means for supplying low pressure gas to said low pressure chamber, said radiant having an upper surface sloping downwardly and outwardly such that when cut by a vertical plane extending in the direction of maximum slope the intersection of the surface with the plane is a straight line.

4. An up-shot gas burner as defined in claim 3 in which openings in said wall means connect said high pressure chamber with said low pressure chamber.

5. A burner as defined in claim 1 in which the distribution member is made of cast iron and is continuous across the upper end of the Venturi tube member.

HAROLD D. SCHRADER.
